ELECTRICAL ILLUMINATING DEVICE

Abraham Wolf, Brooklyn, N. Y., assignor to Noma Electric Corporation, New York, N. Y., a corporation of New York

Application June 14, 1934, Serial No. 730,563

10 Claims. (Cl. 240—10)

This invention relates to electrical illuminating devices, and is particularly directed to electric chandeliers.

An object of this invention is to provide a device of the character described, comprising a base and a set of lamps wired in series circuit, the construction being such that the lamps may be removably mounted on the base, whereby the base and the set of lamps may be sold individually and readily assembled, without requiring attaching devices, tools or any particular mechanical skill.

A further object of this invention is to provide a device of the character described, comprising a flexible base on which a plurality of candle simulating members having electric lamps thereon are mounted, the base being adapted to be pressed into greater or less curvature, and means being provided for holding the base in any adjusted shape thereof.

20 A further object of this invention is to provide a neat, attractive decorative electric chandelier of the character described, which shall be comparatively inexpensive to manufacture, comprise few and simple parts, be easy to assemble or 25 adjust into various shapes and which shall nevertheless be practical and efficient to a high degree in use.

Other objects of this invention will in part be obvious and in part hereinafter pointed out.

30 The invention accordingly consists in the features of construction, combinations of elements, and arrangements of parts which will be exemplified in the construction hereinafter described, and of which the scope of application 35 will be indicated in the following claims.

In the accompanying drawing, in which is shown one of the various possible illustrative embodiments of this invention,

Fig. 1 is a front perspective view of a chandelier embodying the invention;

Fig. 2 is a top plan view of the chandelier shown in Fig. 1;

Fig. 3 is a rear elevational view of the structure shown in Fig. 1;

45 Fig. 4 is a cross-sectional view taken on line 4—4 of Fig. 3;

Fig. 5 is an enlarged, detail view of the adjustable connecting element;

50 A feature of the invention is that the base or mounting member for the candle simulating members may be adjusted so as to change the shape of the device;

Fig. 6 is a top plan view of the device showing the base adjusted to a shape different from that 55 shown in the other figures; and

Fig. 7 discloses a modified form of the candle holder.

Referring now in detail to the drawing, 10 designates a chandelier embodying the invention comprising a base 12 preferably made of resilient sheet metal and having a lower edge 13. The upper edges of the base 13 are stepped, forming a top edge 15, symmetrical lower edges 16 on opposite sides of the top edge 15, still lower edges 17 and still lower edges 18. The portion 19 of 10 the base above the edges 16 is provided with rearwardly curved, substantially cylindrical extensions 20. Said extensions 20 may be formed by merely cutting the edges 16 inwardly sufficiently to provide strips or bands which may be bent 15 into curved shape.

The base below the edges 16, 17, and 18 is likewise formed at the ends thereof with inwardly curved cylindrical portions 20. All of these portions 20 are not entirely closed, to provide spaces 20 21 between the end edges thereof and the body of the base 12, for the purpose hereinafter appearing. The lower edges of the cylindrical portions 20 may be formed with inwardly extending tabs 20a preferably cut from the metal thereof, and 25 bent inwardly.

Adjacent the bottom edge 13, the outer ends of the base 12 are formed with rearwardly extending strips 24, bent outwardly at the outer ends 25 thereof to form feet. An extensible interconnecting member 27 serves to interconnect the portions 24. The member 27 may comprise a pair of strips 28 and 29 disposed in a vertical plane and having the inner ends 30 and 31 thereof in overlapping relation. The portion 29 may 35 be formed with a plurality of spaced openings 30, and the portion 28 may be formed at the inner end thereof with a foot 32 adapted to be received within one of the openings 30.

A bolt 34 passing through an opening 35 in the 40 member 28 extends through another opening 30' in member 29 for clamping the members 28 and 29 together. Thus the length of the member 27 may be adjusted by removing the bolt and changing the relation between the members 28 and 29. 45 Thereafter, the bolt may be replaced. Upon shortening the member 27, the base 12 becomes more curved. The shape of the base may thus be readily changed to increase or decrease the curvature thereof.

50 As shown in Fig. 6, the base may be straight instead of curved, the portions 24 of the base being interconnected by a connecting member 27a riveted at one end 27b to one of said portions and having openings 27c adjacent the other 55

end, one of which receives the other of said portions. By engaging the portion 24 on the right of Fig. 6 with an inner opening 27c, the base may be pressed into curved shape and retained in such shape. It will be noted that the contact of the bottom edge 13 of the base 12 and the connecting member 27a with the support on which the member 10 rests, serves to hold the base in upright position. The member 27 further serves to make the base more rigid.

There may be assembled with the base, a lighting outfit 40, comprising a plurality of tubular candle simulating members 41, each having at the upper end thereof a lamp socket 42 to which a lamp 43 may be screwed. The sockets 42 may be interconnected by wiring 44 passing through said members 41, in series circuit and connected to an attachment fitting 47. The lighting outfit 40 may be readily mounted on the base 12 in the manner hereinafter explained.

The wires adjacent the lower ends of the candle simulating members 41 may be first passed through the openings or spaces 21 between the cylindrical portions 20 and the body of the base, 25 and the lower ends of the candle simulating members then frictionally pressed into said cylindrical portions. The inwardly extending tabs 29a serve as stops to limit downward sliding movement of the members 41 within the cylindrical 30 portions 20.

A dominant feature of the invention is the provision of a base and a series connected lighting outfit including the candle simulating members 41 which may be readily assembled on the base 35 without the necessity for fastening devices, tools or particular mechanical skill. Furthermore, the shape of the base may be quickly and readily changed to suit the taste of the user.

In Fig. 7 there is shown a candle holder 20b, 40 similar to the cylindrical candle holders 20 except that the same are bent to overlap the upper edge of the stepped portions of the base 12. With this construction, as the candle simulating member 41 is inserted, the bottom edge thereof will contact the upper edge of the base, thus rendering it unnecessary to form the tab 20a for limiting sliding movement of the candle simulating member.

It will thus be seen that there is provided a 50 device in which the several objects of this invention are achieved, and which is well adapted to meet the conditions of practical use.

As various possible embodiments might be made of the above invention, and as various 55 changes might be made in the embodiments set forth, it is to be understood that all matter herein set forth or shown in the accompanying drawing, is to be interpreted as illustrative and not in a limiting sense.

Having thus described my invention, I claim as 60 new and desire to secure by Letters Patent:

1. In combination with an electric illuminating device comprising a base made of sheet metal comprising an upstanding curved wall, and a horizontal tab extension bent into tubular shape, the end of said tab being spaced from said wall to provide a longitudinal opening, and a candle simulating member having the lower end thereof received within said tubular portion, a lamp socket at the upper end of said candle simulating member, wiring connected to said lamp socket extending through the candle simulating member, said wiring being adapted to be passed through the longitudinal opening upon mounting said candle simulating member on said cylindri-

cal portion, stop means to limit sliding movement between said candle simulating members and said cylindrical portions, and a member interconnecting the outer ends of said base for maintaining the same in curved position, said member being extensible whereby the curvature of said base may be changed. 5

2. A chandelier comprising an elongated base made of flexible, resilient sheet metal and being curved, and a member interconnecting the outer 10 ends of said base for maintaining the same in curved position, and a plurality of candle simulating members mounted on said base, lamp sockets on said candle simulating members interconnected by wiring passing through said candle 15 simulating members, in series circuit, said interconnecting member being extensible whereby the curvature of said base may be changed.

3. In combination with an electric illuminating device, a base having an upstanding wall made 20 of sheet metal, the lower edge whereof is adapted to contact the support on which the wall is placed, said base being of stepped formation and having tabs at each step, said tabs being curved inwardly into substantially cylindrical shape with the base 25 forming a portion of the wall of said cylinder, and series connected lamp sockets mounted on said cylindrical portions, the cylindrical portions being uncompleted to provide longitudinal openings to permit the wires which interconnect the 30 lamp sockets to pass therethrough when mounting the candle simulating members on said cylindrical portions, said cylinders overlying the upper edges of the next lower steps.

4. An electric illuminating device comprising a 35 base made of sheet metal having an upper edge, said base being formed with a tab bent to substantially cylindrical shape, the cylindrical opening formed by said tab overlying the upper edge of said base, and a candle simulating member 40 having the bottom end thereof inserted within said cylindrical portion and contacting the upper edge of said base.

5. In combination with an electric illuminating device comprising a base made of sheet metal, the 45 lower edge whereof is adapted to contact the support on which the base is placed, said base having integral tabs parallel to said edge, each curved into tubular shape, including a portion of the base, and series connected lamp sockets mounted 50 on said cylindrical portions, said tabs being disposed at different distances from said edge, said formed tubes overlying the upper edge of said base.

6. An electric illuminating device comprising a 55 base made of resilient sheet metal comprising an upstanding wall and a tab extension curved into cylindrical shape to include a portion of said base in said cylinder, the end of said tab being spaced from said wall to provide a longitudinal 60 opening, and a candle simulating member having the lower end thereof received within said cylindrical portion, a lamp socket at the upper end of said candle simulating member, wiring connected to said lamp socket extending through the 65 candle simulating member, said wiring being adapted to be passed through the longitudinal opening upon mounting said candle simulating member on said cylindrical portion, said wall being bendable into different curvatures, and 70 means for maintaining said wall at different curvatures, said cylinders overlying the upper edge of said wall.

7. A chandelier comprising a base made of 75 resilient flexible sheet metal provided with integral

tabs curved to form cylinders, whereby said base forms an arc portion of each of said cylinders, tubular candle simulating members adapted to be received within said cylinders, lamp sockets on 5 said tubular candle simulating members interconnected in a series electrical circuit, and a member interconnecting the outer ends of said base for maintaining the same in curved position, said member being extensible whereby the curvature 10 of said base may be changed.

8. An electrical illuminating device comprising a base made of sheet metal comprising an up-standing wall adapted to rest on the lower edge thereof, and a horizontal tab on said wall bent 15 into tubular shape, having the top edge thereof flush with the top edge of said wall, the end of said tab being spaced from said wall to provide a longitudinal opening, and a candle simulating member having the lower end thereof received 20 within said tubular portion, a lamp socket at the upper end of said candle simulating member, wiring connected to said lamp socket extending through the candle simulating member, said wiring being adapted to be passed through the longitudinal 25 opening upon mounting said candle simulating member on said tubular portion, said tubular portion being formed with an integral tab cut out from the wall thereof and extending

inwardly of said tubular portion and adapted to serve as a stop to limit sliding movement of said candle simulating member on said tubular portion.

9. In combination with an illuminating device 5 comprising a base having a vertically disposed wall, said wall being curved about a vertical axis, means engaging the vertical ends of said wall for maintaining said wall in said curved position, said last named means including means for varying 10 the curvature of said wall, and a plurality of series connected lamp sockets mounted on said base.

10. A chandelier comprising an elongated base 15 made of flexible resilient sheet metal and having a curved wall, the lower edge whereof is adapted to contact the support on which the base rests, a relatively rigid member interconnecting the outer ends of said wall for maintaining the same 20 in curved position, said member being extensible whereby the curvature of said base may be changed, and a plurality of candle simulating members mounted on said base, lamp sockets on 25 said candle simulating members interconnected by wiring passing through said candle simulating members in series circuit.

ABRAHAM WOLF.
